DESIGN FOR A CONDIMENT AND CLOCK UNIT FOR COOKING STOVES

Richard I. Felver, Pittsburgh, Pa., assignor to
Standard Gas Equipment Corporation, Balti-
more, Md., a corporation of Maryland

Application September 26, 1946, Serial No. 133,600

Term of patent 14 years

(Cl. D81—25)

To all whom it may concern:

Be it known that I, Richard I. Felver, a citizen
of the United States, residing at Pittsburgh,
county of Allegheny, State of Pennsylvania, have
invented a new, original, and ornamental Design
for a Condiment and Clock Unit for Cooking
Stoves, of which the following is a specification,
reference being had to the accompanying draw-
ing, forming part thereof.

Figure 1 is a top plan view of my new design
for a condiment and clock unit for cooking stoves.

Figure 2 is a front elevational view thereof.

Figure 3 is an end elevational view thereof.

I claim:

The ornamental design for a condiment and
clock unit for cooking stoves, as shown.

RICHARD I. FELVER.
